(57) **CLAIM**

The ornamental design for a battery and label, as shown and described.

DESCRIPTION

FIG. 1 is a front view of a battery and label showing our new design;

FIG. 2 is a perspective view thereof;

FIG. 3 is a rear view thereof; and,

FIG. 4 is a front view of the label shown in isolation as it appears an unassembled state from the battery.

The claimed design is directed to the appearance of the battery and label in an assembled state as shown in FIGS. 1 through 3. The label is shown in isolation and extended generally flat in FIG. 4 for the purpose of showing aspects of the design that may not be apparent from the other views. The broken line showing the remainder of the battery is for illustrative purposes only and forms no part of the claimed design.
